TRACTOR HITCH MOUNTING FRAME

Paul D. Abbott, P.O. Box 187, Blytheville, Ark.

Filed Nov. 6, 1964, Ser. No. 82,503

Term of patent 3½ years

(Cl. D40—1)

FIG. 1 is a front perspective view of a tractor hitch mounting frame embodying my new design;

FIG. 2, a side elevation thereof;

FIG. 3, a front elevation;

FIG. 4, a bottom plan view; and,

FIG. 5, a fragmentary top plan view.

I claim:

The ornamental design for a tractor hitch mounting frame, as shown.
